INCINERATOR ASH CAN AND SIFTER
Margaret M. Sabol, 150 S. Rose Blvd., Akron, Ohio
Filed Feb. 20, 1961, Ser. No. 100,479
1 Claim. (Cl. 209—374)

This invention relates to incinerators and more particularly to a combination incinerator ash can and sifter assembly.

It is an object of the present invention to provide a combination incinerator ash can and sifter which will facilitate the handling of incinerator ashes and which will facilitate the sifting thereof and transfer of sifted ashes to fertilizer purposes.

A further object of the present invention is to provide an incinerator ash can and sifter assembly of the above type which can be easily handled, is clean in use, and extremely sturdy over prolonged periods of use.

Other objects of the invention are to provide an incinerator ash can and sifter bearing the above objects in mind which is of simple construction, has a minimum number of parts, is inexpensive to manufacture and efficient in operation.

For other objects and for a better understanding of the invention, reference may be had to the following detailed description taken in conjunction with the accompanying drawing, in which:

FIGURE 1 is a side elevational view, with parts broken away, of a combination incinerator ash can and sifter assembly made in accordance with the present invention in assembled relationship;

FIGURE 2 is a side elevational view of a sifter cage forming a part of the present invention removed from the assembly shown in FIGURE 1;

FIGURE 3 is a bottom plan view of the cage shown in FIGURE 2; and

FIGURE 4 is a top plan view of the cage shown in FIGURE 2.

Referring now more in detail to the drawing, an incinerator ash can and sifter assembly 10 made in accordance with the present invention is shown to include a substantially cylindrical receptacle 12 having an interior compartment 14 with a lid 16 and a carrying handle 18.

A cage type sifter 20 is removably mounted within the interior of the receptacle 12, and includes a plurality of substantially rigid vertical rods 24 that support a mesh type side wall 22. Annular rod type frames 26 are secured to the opposite ends of the rods 24, and are further secured to individual end walls 28, 32. The lower end wall 28 is provided with a plurality of apertures 30 through which sifted ashes may pass, whereas the top plate 32 is provided with similar apertures 34 and an enlarged central opening 36 into which ashes and debris from the incinerator may be inserted while the cage is

2

still within the receptacle 12, upon the removal of the lid 16 therefrom.

In actual use, the debris from the incinerator is placed into the sifter cage 20 in a conventional manner. Upon emptying the can, the sifter cage 20 is removed from the receptacle 12, and rolled along a lawn, or the like, to be fertilized upon the wheel-like end plates 28, 32. During such rolling movement, the ashes are sifted through the mesh side wall 22 into direct contact with the ground being fertilized. It will thus be recognized that in rolling the cage sifter 20 along a lawn, the ashes are deposited close to the roots of the grass, thus minimizing unsightly appearance and deriving the most benefit from the ashes so deposited.

It will also be recognized that this device is extremely sturdy, and can be readily handled in a simple and convenient manner.

While various changes may be made in the detail construction, it shall be understood that such changes shall be within the spirit and scope of the present invention as defined by the appended claim.

What I claim as new and desire to protect by Letters Patent of the United States is:

An incinerator ash can and sifter comprising in combination a receptacle, a lid removably mounted upon said receptacle, a perforated cage removably mounted within said receptacle, roller means carried by said cage for rollably supporting said cage for movement along a lawn surface, said receptacle further comprises a substantially cylindrical enclosure having a carrying handle, and said lid is removably supported upon the top of said receptacle, said perforated cage further comprises a substantially rigid frame having a mesh type side-wall accommodating the passage of ashes therethrough, said roller means further comprises a pair of end plates, said end plates being secured to the opposite ends of said mesh side-wall, one of said end plates defining a central opening accommodating the insertion of debris from an incinerator, wherein said end plates further comprise a plurality of ports accommodating the passage of ashes outwardly therethrough during the rolling of the cage upon a lawn.
